UNITED STATES PATENT OFFICE.

REUBEN D. ALEXANDER, OF EUREKA SPRINGS, ARKANSAS.

MECHANICAL HAMMER.

Application filed September 24, 1919. Serial No. 325,845.

To all whom it may concern:

Be it known that I, REUBEN D. ALEXANDER, a citizen of the United States, residing at Eureka Springs, in the county of Carroll 5 and State of Arkansas, have invented certain new and useful Improvements in a Mechanical Hammer, of which the following is a specification.

This invention relates to mechanical hammers and more particularly to a motor actuated hammer in which the body of the hammer is formed by an internal combustion engine directly connected to the striking element, whereby the motion of the 10 striking element is directly received from the actuation of the motor.

One of the objects of the invention is to provide a hammer which will have an integral gasoline motor of the combustion type 20 directly connected thereto whereby the actuation of the piston of the motor will cause the hammer element to be reciprocated in a manner that will cause a forcible blow to be struck by the hammer when in use.

25 A further object of this invention is the provision of a device of this character which consists of comparatively few parts and is simple in construction, but durable and well adapted to withstand the rough 30 usage to which devices of this character are ordinarily subjected.

For a full description of the invention and the advantages and merits thereof, reference is to be had to the following description and accompanying drawings, in 35 which:

Figure 1 is a side elevation of the device constructed in accordance with my invention.

40 Figure 2 is a longitudinal section through the same, and

Figure 3 is a bottom plan showing the operating means for rotating the tool.

45 Referring to the drawings, wherein is illustrated the preferred form of my invention, in which like characters of reference indicate like or corresponding parts throughout the several views, the crank case 1 is of substantially circular formation and 50 has mounted thereon a cylinder 2, the crank case and cylinder forming the frame work for the motor. The motor also is constituted as a part of the hammer and is therefore readily portable. The fly wheel 3 is 55 mounted within the crank case 1 and turns on the motor shaft 21 which is of the usual

crank shaft formation. The crank shaft 22 is connected, by means of a connecting rod 4 with a piston head 5 which is mounted in the cylinder 2. The wrist pin 10 in the cylinder which forms a connection for the connecting rod with the piston also receives the yoke member 9 which has its lower end provided with the diverging arms the terminals of which are connected to a leaf spring 60 65 12. The leaf spring 12 is connected intermediate its ends with one end of the hammer 11 so that when the piston 5 is reciprocated the hammer will also be reciprocated. An adjustable support constituting rotatable collar 14 is provided to adjust the position of the drill 13 with respect to the hammer 11 which may be of any preferred type such as is used in various drilling operations. The drill is suitably connected to 70 the collar 14 as by a key 23 and the collar is screw threadedly engaged with the rotatable sleeve 19 mounted as shown on an extension 19' of the crank case, and this sleeve is provided with an annular series of teeth 80 85 20 which are engaged by a pawl 18 carried by a vertical rod 17 which is journaled in a frame on one side of the crank case. The engine or crank shaft is provided with a gear on one end which is indicated by broken lines in Fig. 1 and this gear engages the gears on two cam shafts 8 which actuate the valve rods 7 whereby the intake and exhaust valves 6 will be properly actuated. One of the shafts 8, however, is provided 90 with a cam member which engages a projection or arm 16 on the rod 17 and this cam indicated at 15 is rotatable with the shaft so that the rod 17 will be actuated at certain times whereby the dog 18 will turn the 95 sleeve 19 by engaging the annular rack 22 for rotating the drill 13 during its vertical movement. The arm 16 is held in engagement with the cam 15 by a coil spring 24.

100 The operation of the mechanism is readily understood from the above description and it will be noted that continued actuation of the gasoline motor will impart a forcible blow to the hammer whereby the drill will 105 be actuated.

The foregoing description and accompanying drawings have reference to what might be considered to be the approved or preferred form of my invention. I desire 110 it to be understood that I may make such changes in construction, combination and

arrangement of parts, materials, dimensions, et cetera, as may prove expedient and fall within the scope of the appended claims.

5 Having thus fully described my invention what I claim as new and desire to secure by Letters Patent, is:—

A mechanical hammer comprising a crank case, a cylinder extended from the crank case, a piston and connecting rod mounted in the cylinder and connected to the crank shaft in the crank case, a hammer, a yoke connecting the said piston and provided with diverging arms, a leaf spring mounted

on one end of the hammer and having its terminals fixed to the ends of the said diverging arms, a sleeve embracing the said hammer, a drill connected to the sleeve, and means for actuating the said sleeve whereby the drill may be rotated during reciprocation. 15

20 In testimony whereof I affix my signature in presence of two witnesses.

REUBEN D. ALEXANDER.
